UNITED STATES PATENT OFFICE.

MAX MAURAN, OF NIAGARA FALLS, N. Y., ASSIGNOR TO THE MATHIESON ALKALI WORKS, INC., OF NEW YORK, N. Y., A CORPORATION OF VIRGINIA.

MULTIPLE-UNIT TANK CAR.

Application filed May 18, 1922. Serial No. 562,001.

To all whom it may concern:

Be it known that I, MAX MAURAN, a citizen of the United States, residing at Niagara Falls, in the county of Niagara, State of New York, have invented certain new and useful Improvements in Multiple-Unit Tank Cars; and I do hereby declare the following to be a full, clear, and exact description of the invention, such as will enable others skilled in the art to which it appertains to make and use the same.

This invention relates to improvements in multiple unit tank cars designed for the transportation of a plurality of tank cars containing liquefied gases. More particularly, the improvement relates to improvements in multiple unit tank cars of the character described in my prior application, Serial No. 534,642, filed February 7, 1922.

In the transportation of liquefied gases, such as liquefied chlorine, liquefied sulphur dioxide, etc., it has been customary heretofore to ship the liquefied gases in relatively small containers, especially designed and constructed for withstanding the high pressures of the liquefied gases contained therein. The shipment of the liquefied gases in this way involves an excessive cost for the containers and for their shipment (both when full and returning them empty). The amount of the liquefied gases that can be transported in such a container is, moreover, small, and, for large shipments, an excessive number of the small individual containers is necessary. If tank cars having a single large tank are used for transporting such liquefied gases, it is difficult to prevent injury or weakening of the tanks by corrosion, particularly with corrosive gases and where the tanks are insulated to protect them from overheating during transportation; while the transportation of a single tank car of the liquefied gases presents a potential risk of a major order in case of accident to the car.

According to the present invention, a multi-tank car is provided which enables liquefied gases to be transported in large containers and in carload lots, with equal or greater safety than when shipped in small containers, and with added advantages in the handling and shipment of large quantities of the liquefied gases.

The present invention provides a multi-

tank car for transporting a relatively large number of tanks, for example, each of about one-ton capacity, the tanks being constructed to withstand safely the pressures to which the liquefied gases are subjected, and the tanks being individually mounted and supported on the car and securely held in place during transportation, but being so secured and held that they can be readily removed and replaced when desired.

In transporting tanks of a liquefied gas, which is confined under a heavy pressure, and which may be highly poisonous and destructive if released from the container, it is important to insure that the tanks shall be securely held in place without danger of accidental removal from the car and also securely held from motion on the car, either transversely or longitudinally. If the tanks are placed on end, with their axes vertical, the pitching and rolling motion of the car is exaggerated on the tank.

The multi-tank car of the present invention is constructed to hold a relatively large number of tanks securely and without danger of accidental displacement or movement on or from the car, even with the varied motions of pitching and rolling, and of sudden stopping and starting, to which the car may be subjected in transit, and which subject the load of the car to the same varied motion.

According to the present invention, the car structure itself is so constructed as to provide individual cradles for holding a considerable number of tanks on the car, and, in connection with the series of individual cradles, there is provided means for holding the tanks on the cradles and preventing them either from transverse motion transversely of the car, or motion longitudinally of the car, as well as preventing their removal from their respective cradles until released therefrom. The nature and advantages of the invention will more fully appear from the following more detailed description.

In my prior application, Serial No. 534,642, I have illustrated and described a multiple unit tank car in which the cradles are longitudinally arranged and the drums or tanks transversely arranged, so that the drums or tanks are prevented from rolling motion longitudinally of the car by the

cradles. In the improvement of the present invention the car construction is such as to provide transversely arranged cradles for holding the drums or tanks longitudinally on the car, so that they are prevented from rolling motion laterally by the cradles; and clamping means is provided for securing the drums on the cradles, so that they cannot be raised therefrom and so that they cannot move longitudinally of the car until the clamping means is released.

10 The tanks used in the new car construction may be of about one-ton capacity and of generally cylindrical shape and provided with suitable valves, safety devices, etc. They may have an over-all length of about eighty inches, or somewhat less than the width of an ordinary railroad car.

15 For transporting liquefied gases, such as liquid chlorine, the safety devices should be of such a character as to permit release of the gases in case of fire or undue heating, before the pressure due to the heat becomes excessive. The safety devices may be in 20 the form of fusible plugs which will melt at a relatively low temperature, for example, around 150° F. In case of injury or overheating of one of the tanks or drums, its contents will be released in a 25 gradual and progressive manner, while the other tanks may retain their contents without injury.

25 The car construction is equally adapted for the transportation of full containers (filled with the liquefied gas) and empty containers, so that the car can be shipped with a load of full containers and returned with a load of empty containers, without delay other than that occasioned by the 30 unloading and loading of the car. The car is, moreover, so constructed as to permit ready loading and unloading, while it is, nevertheless, designed and constructed to provide, as a part of the car structure, supporting and bracing means as well as cradles 35 for holding the tanks with their axes horizontal and longitudinal of the car. In connection with each cradle and tank, means is provided for detachably securing the tank 40 to the cradle so that the tank will be securely held in place, but that it may, nevertheless, be unfastened and removed when desired, and a new tank either empty or 45 filled, inserted to take its place.

50 In constructing the car, the cradles and supporting means therefor are carried directly by the car frame so that the provision of the usual platform of a freight car is made unnecessary. However, the arrangement of a series of tanks longitudinally of the car presents an impediment to the easy and safe passage of the brakeman along the car, especially when the car is in rapid motion. In order to overcome this 55 difficulty, the car is provided with special

passageways along the sides of the car, and also at the ends, so that the brakeman may easily and safely pass along the sides of the car from one car to another without danger, even during rapid travel of the car in transit. The car construction as a whole, accordingly, enables a series of tanks of large capacity to be safely transported and held in place, but detached and removed and replaced when desired, while also enabling the 70 brakeman to travel along the car, on gangways at the sides of the car, with the construction and arrangement of the car as a whole nicely balanced and with a load distributed in a substantially uniform manner 75 transversely of the car.

80 The accompanying drawings illustrate the preferred construction of the multi-tank car of the invention, the construction being shown in a somewhat conventional and diagrammatic manner, but it is intended and will be understood that the invention is illustrated by and not limited to the specific construction so illustrated and described.

85 In the drawings—

Figure 1 is a plan view of the improved car with parts broken away.

Figure 2 is a side view, with some of the 90 containers removed.

Figure 3 is an enlarged partial side view 95 with parts in section.

Figure 4 is a section on the line 4—4 of Figure 1.

Figure 5 is a detail of the clamping 100 mechanism, with parts in section.

Figure 6 is an enlarged partial plan view.

Figure 7 is a transverse section.

Figure 8 is a detail of the means for holding the containers to their seats.

Figure 9 is a view at right angles to Figure 8.

Figure 10 is a partial transverse section showing a modified form of holding mechanism.

Figure 11 is a side view of Figure 10.

Figure 12 is a transverse section showing an alternate construction.

110 In the embodiment of the invention shown in Figures 1 to 9, the frame or body of the car is made up of a central sill 1, constructed as a box girder, and a plurality of cross girders 2 supported by the central sill. Near the ends of the car other girders 3 of stronger construction than the girders 2 are provided, and trucks indicated at 4 are pivoted to the car at the girders 3. At the ends of the sill, girders 5 are arranged, and the girders 5 are connected to the girders 3 by longitudinal plates 6 and braces 7 as shown. Thus 115 there is provided a stronger construction at the ends of the car than intermediate the ends, and this construction provides a suitable frame work for supporting and holding the car as a whole upon the trucks.

120

125

130

As shown more particularly in Figure 4, the girders 2 are of lighter construction at their outer ends, and at the said outer ends they support a runway 8, and a hand rail 9 at the outer side of the runway. Each girder 2 carries a series of blocks 10 and 11, the blocks 10 having their upper corners concave, while the blocks 11 have their upper inner corners concave. Each pair of blocks 10 and 11 forms between them a seat for engagement by a container 12, and the blocks 10 form between them a third seat for engagement by another container. Thus there is provided on each girder 2 three seats, capable of holding three containers, and the girders 2 are so spaced that each pair will support three containers, the girders being spaced in such manner that the seats or cradles formed by the blocks 10 and 11 will be near the ends of the containers. A guard plate 13 is arranged at the inner side of each runway 8, and the said guard plates rest against the outer faces of the adjacent blocks 11.

Any suitable means may be provided for clamping the containers on the seats against movement in the direction of the long axes of the containers, and against upward movement, the cradles or blocks 10 and 11 holding the containers against rolling movement laterally of the car. In Figures 1 to 5, inclusive, the said means is in the form of rods 14, which are pivoted to the girders as indicated at 15, a rod being arranged at each end of each container, that is, at each end of each cradle. A hook 16 is arranged to move on each rod, each hook having a bearing sleeve engaging the rod, and the hooks are designed to engage the chimes of the containers, as shown more particularly in Figure 5. Each of the hooks 16 is rotatably connected to a nut 17 threaded on the rod, and it will be evident that by turning the nut the hook may be moved longitudinally of the rod, to engage or disengage the hook with the chime. Each rod has a head 18 for preventing entire disengagement of the nut and hook.

Referring to Figure 3, it will be seen that the ends of each row of containers are flush, that is, in the same plane, and that each row of containers is spaced apart from adjacent rows far enough to provide a passage between adjacent rows, so that the brakeman, for instance, can pass the entire length of the car at either side, or may pass transversely of the car between any two adjacent sets of containers, and so that ready access may be had to the clamping means between the containers. Hand rails 19 are arranged at the ends of the car, the hand rails extending transversely from near one hand rail 9 to near the other, but being spaced apart from said hand rails far enough to provide a passageway.

In Figures 6 and 7 there is shown an alternative arrangement of means for clamping the containers on the seats. Instead of means being provided for engaging the chimes of the containers, clamping bands 20 of curved formation are provided. At the opposite sides of the car, the bands 20 are hinged to rods 21 extending upwardly from the girders, and intermediate the sides of the car the bands are connected to rods 22 extending upwardly from the blocks 10. Each of the rods 22 carries a washer 23 having grooves or depressions 24 in its under face, and at opposite sides of the rod, for engagement by hoods 25 on the adjacent ends of the bands 20. A nut 26 is threaded on to the rod above the washer, and it will be evident that by turning the nut in the proper direction the bands may be clamped down upon the containers.

In Figures 10 and 11, means for holding the containers on their seats is provided in the form of chains 27, each chain being in two sections. Each section of chain is connected to an eye-bolt 28 on the car body, and the adjacent ends of the corresponding sections are connected by a clamp indicated at 29. The said clamp is in the form of a hook pivoted to one chain section, and engaging the end of the other chain section.

With the arrangement of the containers on the car in the manner illustrated and described, the car when loaded is evenly balanced and the individual drums or containers are securely held in place against accidental movement. The sidewise movement of the containers is prevented by the transverse cradles and by the clamping means which clamp the containers on the cradles. The longitudinal movement of the containers on the car is prevented by the frictional engagement of the containers with the cradles and by the clamping means. The containers are thus able to withstand the abrupt stops and starts of the car during shifting or in transit.

The arrangement is, nevertheless, such that ready access may be had to any particular container to detach the clamping devices and permit its removal from the car. A sufficient space is provided between the containers to provide a passageway and to provide access to the ends of the containers where the clamping devices are secured to the ends. The arrangement is, moreover, such that the series of containers do not extend to the extreme outer edge of the car, but terminate short of the side, so that a safe passageway may be provided for the brakeman along the sides of the car. The passageway along the sides and ends of the car and between the rows of containers enables any part of the car to be readily reached and any desired drum or drums to be removed when desired.

The car is well adapted for loading and unloading since by releasing the respective clamping devices the full or empty drums can be lifted off the cradles and other drums substituted and secured in place. A minimum of time is accordingly lost when the car reaches its destination, either in loading or unloading it, or in both unloading or loading it. The drums can be readily removed, for example, by means of an overhead crane, and carried to their places of storage or of use. The car can thus be readily loaded and at its destination unloaded, reloaded and again started in transit. It enables a relatively large number of tanks to be readily transported and safely secured in place against accidental movement during transportation.

The present invention, accordingly, presents advantages similar to those of an ordinary tank car, having a single tank, while it avoids the objections and disadvantages of such a tank car, and, in addition, has added advantages in enabling liquefied gases to be safely transported in relatively large units and with the containers at all times accessible for ready inspection and testing. This inspection and testing is of particular importance where the gases transported are corrosive in character.

The multiple unit tank car of the present invention is also adapted for the transportation of noncorrosive products, such as casing-head gasoline, where it is imported to prevent escape of highly volatile dissolved gases, and where the containers are required to withstand the pressure which such gases may exert.

In the embodiment of the invention shown in Figure 12, the car indicated at 30 has a runway indicated at 31, arranged between the longitudinally extending tanks 32. With the tanks arranged in sets of three, the runway would have two tanks on one side and one on the other, and in order that the load may be properly balanced, it is preferable that the runways be in sections, a section for each set of tanks, and that the sections of the sets be staggered. If the tanks are arranged in sets of four, the runways would have two tanks on each side, and would be continuous.

While I have illustrated and described the preferred embodiments of the invention, I do not limit myself thereto, inasmuch as variations and modifications may be made therein without departing from the spirit and scope of the invention as set forth in the accompanying claims.

I claim:

1. A multiple unit tank car, comprising a body composed of a central longitudinally extending sill and transverse girders, said girders supporting seats for receiving substantially cylindrical drums arranged with

their long axes longitudinal to the car, drums in the seats, and means for clamping the drums in the seats.

2. A multiple unit tank car, comprising a body composed of a central longitudinally extending sill and transverse girders, said girders supporting seats for receiving substantially cylindrical drums arranged with their long axes longitudinal to the car, drums in the seats, and means for clamping the drums in the seats, the seats being arranged in sets, the members of each set being transversely arranged in the car.

3. A multiple unit tank car, comprising a body composed of a central longitudinally extending sill and transverse girders, running boards supported by the girders at opposite sides of the car, and blocks secured to the girders and forming between them seats having their long axes longitudinal to the car, substantially cylindrical containers in the seats, and means engaging the containers for holding them to the seats.

4. A multiple unit tank car, comprising a body composed of a central longitudinally extending sill and transverse girders, running boards supported by the girders at opposite sides of the car, blocks secured to the girders and forming between them seats having their long axes longitudinal to the car, substantially cylindrical containers in the seats, and means engaging the containers for holding them to the seats, the seats being arranged in sets to hold the containers with the adjacent ends of adjacent sets spaced apart.

5. A multiple unit tank car, comprising a body composed of a central longitudinally extending sill and transverse girders, seats supported by the girders, substantially cylindrical containers held in the seats, said seats being arranged to hold the containers with their long axes parallel with the long axis of the car, and in sets, with the adjacent ends of the containers of the sets spaced apart from each other.

6. A multiple unit tank car, comprising a body composed of a central longitudinally extending sill and transverse girders, seats supported by the girders, substantially cylindrical containers held in the seats, said seats being arranged to hold the containers with their long axes parallel with the long axis of the car, and in sets, with the adjacent ends of the containers of the sets spaced apart from each other, a runway supported by the girders at each side of the car, and a hand rail outside each runway.

7. A multiple unit tank car, comprising a unitary open frame, seats supported by and unitary with the frame, cylindrical containers held in the seats, said seats being arranged to hold the containers with their axes substantially parallel with the axis of the car.

8. A multiple unit tank car, comprising a unitary frame having a plurality of sets of seats, the members of each set being arranged transversely of the car and forming a series of seats adapted for supporting cylindrical containers longitudinally of the car, and means secured to the frame adapted for clamping the containers to the seats. 30
9. A multiple unit tank car, comprising a body composed of a central longitudinally extending sill and transverse girders, said girders supporting seats adapted for receiving substantially cylindrical drums arranged with their axes longitudinal to the car, and means adapted for clamping said drums in the seats. 35
10. A multiple unit tank car comprising a unitary frame having a plurality of sets of seats, the members of each seat being arranged transversely of the car, the seats extending longitudinally of the car, said seats being adapted to hold a cylindrical container longitudinally and means for holding the containers to the seats. 40
11. A multiple unit tank car comprising a body composed of a central longitudinally extended sill and transverse girders, said girders supporting seats for receiving substantially cylindrical drums arranged with their long axes longitudinally to the car and means for clamping drums in the seats. 45
12. A multiple unit tank car comprising a body composed of a central longitudinally extended sill and transverse girders, running boards supported by the girders at opposite sides of the car and blocks secured to the girders and forming between them seats having their long axes longitudinal to the car, and means for clamping drums in the seats. 50
13. A multiple unit tank car comprising a body composed of a central longitudinally extended sill and transverse girders, seats adapted to hold cylindrical containers supported by the girders, said seats being arranged to hold containers with their long axes parallel with the long axes of the car, said seats being arranged in sets and spaced apart from each other whereby the adjacent ends of the containers are mounted in spaced relation, a runway supported by the girders at each side of the car and a hand rail outside each runway. 55

In testimony whereof I affix my signature.

MAX MAURAN.
